CLAIM

I claim the ornamental design for a CPAP mask-cleaning sponge, as shown and described.

DESCRIPTION

FIG. 1 is a front view of the CPAP mask-cleaning sponge.
 FIG. 2 is a left side view of the claimed design.
 FIG. 3 is a right side view of the claimed design.
 FIG. 4 is a top view of the claimed design.
 FIG. 5 is a bottom view of the claimed design; and
 FIG. 6 is a perspective view of the claimed design.
